UNITED STATES PATENT OFFICE.

ALBERT E. HALL, OF CAMBRIDGE, MASSACHUSETTS, ASSIGNOR TO HIMSELF
AND EDGAR HALL, OF SAME PLACE.

HAT AND GARMENT HOOK.

SPECIFICATION forming part of Letters Patent No. 429,346, dated June 3, 1890.

Application filed January 4, 1890. Serial No. 335,903. (No model.)

To all whom it may concern:

Be it known that I, ALBERT E. HALL, a subject of Her Majesty the Queen of Great Britain, and a resident of the city of Cambridge, 5 in the county of Middlesex and State of Massachusetts, have invented certain new and useful Improvements in Hat and Garment Hooks, of which the following is a full, clear, and exact description.

10 This invention relates to hooks for hanging hats, coats, garments, or other wearing-apparel, &c.

The invention, in substance, consists of a hook-arm suitable to receive and hang a hat, 15 &c., on it, and which at its inner end is hinged or fulcrumed on a suitable support and has an upward extension swinging in common with it in combination with an arm to close and open, and when closed to guard the space 20 within and between the hook and its support, and which at its inner end is hinged or fulcrumed on a suitable support, a connection between said upward extension of the hook and said guard and a spring or other 25 elastic resistant to act on the guard to hold it opened and to allow it to be closed and automatically to close it all, so that with the hook, the guard, and connection of hook and guard in their normal positions the hook is opened 30 for placing and hanging a hat, &c., on it, and with a hat, &c., hung on the hook its weight operates to cause it to close and to hold the guard closed so as to the hook, thereby securing the hat, &c., against accidental escape 35 from the hook, and with the weight of the hat removed from the hook the guard is automatically opened from the hook and it and hook and their connection all returned to their normal position.

40 In the drawings forming part of this specification, Figure 1 is a side elevation of the garment-hook of this invention in the normal position of all of its parts, and showing by dotted lines their position when a hat is placed 45 and hung on the hook. Fig. 2 is a plan view, in detail and enlarged, of parts of the hook, Fig. 1. Fig. 3 is a side view, enlarged, of a modification of the spring and its application.

In the drawings, A is a plate making the 50 support for the hook of this invention and

for a supplemental hook B, located below it. This plate is to be adapted, as well known or otherwise, suitably for its attachment to the wall of a room or other place.

The hook of this invention obviously, pref- 55 erably, is combined with a plate A or other suitable support for it, and it is composed, essentially, of a hook-arm C at its inner end fulcrumed on the plate A and having an up- 60 ward extension C², an arm or guard D at its inner end fulcrumed on the plate A above 65 and directly over and in the vertical plane of the hook-arm C, a device E—such as a link— 70 connecting upward extension of hook-arm C and the arm or guard D, and a spring E or other elastic resistant to act on the arm D to 75 open it and hold it opened from the hook-arm C and to allow it to be closed thereon. The hook-arm C is of a shape, well known or otherwise, suitable for the hanging of a hat, coat, 80 or other garment, &c., on it. The arm or guard D is of a shape to permit it to swing upward from the hook-arm C to open the hook, for a hat, &c., to be hung on it and swing downward toward the hook C, to lie across 85 and thus to close the open space between the outer end and the support of the hook C. The link-arm E at its opposite ends is hung on and confined against escape from the guard D and hook C, and it connects the two, 90 so as to allow the guard to be swung toward or away from the hook and the hook toward and away from the guard, and the guard to swing away from the hook on a swing of the hook toward the guard, and the spring is ap- 95 plied to swing the guard and thus to open it and to hold it opened from and to allow it to close on the hook, as stated, with a hat, &c., hung or weight otherwise on the hook.

As shown, the hook and guard each have a 90 knob at their outer end. Again, as shown, Fig. 2, the spring is a coiled spring, and it is fixed at one end on the support for the fulcrum-pin of the guard and at the other end on said fulcrum-pin, all so as to act by torsion 95 on the guard to open and hold it opened and to permit of its closing.

In Fig. 3 the spring is a bent spring held at one end on the plate A and its other and free end arranged to bear on and by com- 100

pression to move the guard in a direction to open it from the hook and to be compressed in closing the guard on the hook.

From the description given it is plain that 5 on hanging a hat (shown in part by dotted lines, Fig. 1) on the hook the guard is automatically closed upon the hat, thereby guarding it against accidental escape. Furthermore, it is plain that on removing the weight 10 of the hat from the hook the guard then automatically opens, leaving the hat free to be removed, the advantages of all of which are obvious, not only particularly as to its use for hanging hats of all kinds, but also as to hanging 15 other articles of wearing-apparel or garments, &c.

The supplemental hook B, with the hook of this invention used for hanging a hat, is convenient for hanging a coat.

20 Having thus described my invention, what I claim, and desire to secure by Letters Patent, is—

A hook for hanging hats, &c., composed of a hook C, having an upright extension C² at a more or less right angle thereto and thereat 25 fulcrumed on a stationary support, in combination with an arm or guard D, located above and in the vertical plane of said hook and fulcrumed on a stationary support, a link E, jointing and connecting said guard at or near 30 its fulcrum portion to the upper end portion of said upright extension C² of said hook, and a spring F, fixed at one end and at its other end adapted to press on the guard E to hold it opened from and to allow it to be closed toward the hook C, substantially as described, 35 for the purpose specified.

In testimony whereof I have hereunto set my hand in the presence of two subscribing witnesses.

ALBERT E. HALL.
